UNITED STATES PATENT OFFICE

2,615,608

CLOSURE APPLYING MECHANISM

Samuel Davison Young, Rugby, England

Application February 25, 1948, Serial No. 10,896
In Great Britain February 3, 1944Section 1, Public Law 690, August 8, 1946
Patent expires February 3, 1964

1 Claim. (Cl. 226—86)

1

This invention relates to caps or closures for jars, bottles, tin boxes and like containers, furnished with a welt, bead or the like formed to provide a recess or re-entrant portion adjacent the mouth or opening of the container designed for assisting in securing a cap or closure in position thereon.

The invention consists in a closing head for securing caps or closures furnished with a peripheral flange having a false wire, beaded or otherwise thickened outward extending continuous or uninterrupted edge or extremity on containers furnished with a welt, bead or the like or otherwise formed to provide a recess or re-entrant portion below the mouth of the opening thereof, adapted to encircle the flange of the cap or closure and provided at a plurality of spaced intervals with elements projecting inward and formed to effect local displacement of the edge of the flange of the cap or closure in a downward and radially inward direction leaving intervening portions of the flange free.

The elements adapted to secure local inward and downward displacement of the continuous edge of the cap or closure are in effect ribs and they will normally be furnished adjacent the open end of the closing head with inclined or radiussed portions to facilitate the entry and gradual displacement of portions of the flange of the cap or closure in a downward and radially inward direction by the movement of the head in a direction parallel with the axis of the container.

The number of points with which the elements are provided in the head for effecting displacement of the flange may be varied in accordance with requirements.

In the case of a head designed for engaging the cap or closure, on a standard 1 lb. jam jar, it may be six, or preferably twelve, while in the case of containers of the character employed for potted meat, four or preferably eight may be sufficient.

The invention will be described further in detail and by way of example with reference to the accompanying drawings, in which:

Figure 1 is a view in elevation of a cap or closure secured in accordance with the invention to a standard 1 lb. jam jar.

Figure 2 is a corresponding plan view.

Figure 3 is a view in elevation partly in section of a jar furnished with a peripheral flange, such as is commonly employed in packing potted meats having secured to it in accordance with the invention a cap or closure.

Figure 4 is a view in sectional elevation of a sealing head for use in securing the cap or closure in position.

2

Figure 5 is a sectional plan view on planes indicated by the line V—V in Figure 4.

As will be seen from Figures 1, 2 and 3, the cap or closure is generally of the usual form and is furnished with a flange 1 having a false wire edge 2, portions of which 3 at equally spaced intervals have been deflected inward and under the edge of the welt 4 of a jam jar or below the peripheral flange of a jar such as is used in the vacuum packing of potted meats, thereby securing the cap or closure in position with for instance a washer or joint ring 5 bearing on the top of the welt.

For effecting this connection a closing head generally as illustrated in Figures 4 and 5, is used.

As will be seen this closing head which is adapted to be engaged with the ram of a press of known construction, comprises a crown member 6 which forms a housing for a plurality of jaws 7, which are provided with bevelled surfaces 8 adjacent to their lower extremities to facilitate their passage over the false wire or wired edge of the cap or closure and are located in recesses as shown in the upper portion of the housing and extend through gaps between the fingers 9 at the lower extremity of the housing, the jaws being secured in position in the recesses by set screws 10 engaged in a flanged top plate 11 and bearing upon packing pieces 12 contacting with the jaws, the housing being engaged in the top plate by screws 13.

In the construction shown, through the housing in the top plate extends the stem 14 of a pressure plate 15 the purpose of which is to hold the cap in position against its sealing ring or the like on the flange or the equivalent portion of the container in order that the sealing operation may be completed by the downward movement of the closing head.

While in the above detailed description the invention has been described in its application to securing caps or closures to glass jars, it is to be understood that it may be applied to securing caps or closures on containers formed of sheet metal of the type in which in the peripheral wall 45 of the container there is provided an annular recess somewhat below its upper or outer extremity.

It is therefore clear that my present invention provides a closing head for cooperation with closures of the type having a depending peripheral flange, which flange is provided with an uninterrupted, thickened, radially extending outer edge. The closure head being operable and dimensioned to encircle the flange of the closure 55 or cap and secure the same to a container of the

type having a welt or bead adjacent the mouth which projects outwardly of the body of the container and provides a recess or reentrant portion below the mouth of the container. The closure head of the invention comprises a crown member including a body from which depends a skirt. The skirt is provided with longitudinally extended, circumferentially spaced slits. The body portion has greater diametrical extent than the skirt and is provided with longitudinally extending grooves on the periphery thereof in longitudinal alignment with the slits. Within each groove and extending longitudinally of the axis of the crown member are provided jaw members. Therefore the jaw members will correspond in number to the number of slits and thus the jaw members and the several areas of skirt between each slit constitute respective finger means. The finger means on the skirt therefore being integral with the crown and means in the form of washers and set screws passing through apertures in a flanged top plate, or cap member rigidly and detachably secure the upper portion of each of the jaw members in the grooves in the body portion of the crown member so as to rigidly and detachably secure the jaw members to the crown with the jaws attached to the crown in cantilever fashion.

A pressure plate is disposed within the skirt in slidable relation with respect to the crown for cooperation with the top of the closure to hold it in position against the container, whereupon downward movement of the closing head proper, that is relative axial movement of the crown member with respect to the pressure plate, effects inward displacement of portions of the uninterrupted thickened outer edge on the peripheral flange of the closure at circumferentially spaced intervals.

The number of local displacements of the outer edge of the cap can be varied by varying the number of the jaw members secured in the grooves in the crown. Each of the removable and detachable jaw members terminates at its lower end with inclined or raised surfaces to facilitate the re-entry and gradual displacement of portions of the cap and these jaw members thus provide in the skirt a plurality of circumferential spaced points which, as shown in the drawings,

extend inwardly of the finger means embodied with the skirt so that they effect the local displacement of the edge on the flange of the cap in a downward and radially inward direction leaving the intervening portions of the flange free. This relationship is clearly shown in Figure 5 where the removable and replaceable jaws have greater radial extent with respect to the axis of the crown than is the thickness in the radial direction of the skirt.

10 I claim:

A closing head for securing caps or closures of the type having a peripheral flange having an uninterrupted, thickened, radially extending edge thereon to containers of the type provided with a welt providing a recess or reentrant portion below the mouth of the container, said head being adapted to encircle the flange of the cap in a closing operation and comprising a crown having a depending skirt, said skirt having circumferentially spaced longitudinal slits therein, a plurality of jaws each including an upper portion and said jaws corresponding in number to the number of slits in the skirt extending longitudinally with respect to the axis of said crown depending therefrom and disposed within said slits, means rigidly and detachably securing the upper portions of said jaws to said crown so that the jaws are attached to the crown in cantilever fashion and said jaws having inner surfaces disposed radially inwards of the adjacent surfaces of the skirt for engaging and effecting local displacement at circumferentially spaced positions of the radially extending edge on the flange of the cap in a closing operation.

35 SAMUEL DAVISON YOUNG.
